UNITED STATES PATENT OFFICE.

TOBIAS J. KAUFMAN, OF CHICAGO, ILLINOIS, ASSIGNOR TO TECK MANUFACTURING COMPANY, OF CHICAGO, ILLINOIS, A CORPORATION OF ILLINOIS.

SANITARY FIXTURE.

Application filed June 21, 1923. Serial No. 646,909.

To all whom it may concern:

Be it known that I, TOBIAS J. KAUFMAN, a citizen of the United States, residing at Chicago, Cook County, Illinois, have invented certain new and useful Improvements in Sanitary Fixtures; and I do hereby declare the following to be a full, clear, and exact description of the invention, such as will enable others skilled in the art to which it appertains to make and use the same.

This invention pertains to sanitary fixtures and more particularly to the provision of improved means for securely attaching and supporting said fixtures directly from the soil pipe.

The object of the invention is the provision of means whereby the fixture, such as a closet bowl, may be quickly and securely so connected to the soil pipe, or to an extension thereof, that the said pipe or connection may bear the weight of the fixture and any additional weight imposed upon the latter.

Another object of the invention is the provision of instrumentalities which may be easily and quickly installed in position to effectively accomplish the purpose above set forth, and at the same time effect a watertight joint between the soil pipe and the fixture.

Other objects of the invention will be made apparent in the following specifications, when read in connection with the drawings forming a part thereof.

In said drawings:

Fig. 1 is a sectional view, partly in elevation, showing a closet bowl secured to an extension of the soil pipe, and

Fig. 2 is a front view of a supporting installation.

Now referring specifically to the drawings. A indicates a closet bowl provided with a rear plate B, adapted to cover an opening in a wall C, and provided with an outlet D positioned for discharge into a soil pipe E or an extension thereof.

It is to be understood that water is delivered to the bowl A, by an inlet F, and passes around the usual rim in the bowl, and through the outlet D to the soil pipe. The outer end of the soil pipe extension E is externally screw-threaded, and an internally screw-threaded coupling member G is screwed onto said extension E, the front peripheral face of said coupling G engaging a packing gasket H located in an annular

recess formed in the rear face of the plate B. The coupling G, on its outer surface, is provided with a circumferential, laterally-extending flange I, for a purpose to be hereinafter explained, and two recesses J, J, are cut in the periphery of said flange, adapted to receive an operating spanner wrench.

Surrounding the coupling G is a yoke member K, having a slightly ovalized opening in its center. Said yoke is adapted to be positioned upon the extension E of the soil pipe, and to be brought forward until its front face engages the rear face of the flange I on the coupling G. The lower portion of the yoke K is provided with a groove L, formed between the front face of the yoke and an upwardly extending lip M formed integrally with the yoke. A downwardly and forwardly projecting arm N is carried by the yoke, and provided with an aperture 70 to receive a bolt O, whereby the arm may be secured to the plate B. The upper portion of the yoke K carries ears P, whereby to receive bolts for fastening the yoke to the plate B, as will be understood. Set screws 80 R extend through the yoke K, and bear upon the coupling G, whereby to non-rotatively retain the yoke and coupling in adjusted position.

In the assembly of the fittings as described, it being understood that the soil pipe extension is approximately in alignment with the opening left in the wall C, the workman places the yoke K over the extension E, and turns the coupling G onto the extension E until the outer periphery of the coupling projects only slightly beyond the outer surface of the wall C. The yoke K is then lifted off the extension E and brought forwardly over the rear portion of the coupling G, until the groove L in the lower portion of the yoke is below the flange I. Because of the oval opening therein, the yoke may then be lifted until the flange I enters the groove L. The set screws R are 100 then applied in position.

With the fittings located as described, and threaded draw-bolts O positioned in the openings in the arm N and ears P, the back plate B of the bowl is pressed against the wall C to cover the opening therein. In this operation it is to be noted that the bolts O pass through suitable apertures in the plate B, and that the projecting end of the coupling G contacts the gasket H in the an-

nular recess in the rear of the plate B. Threaded nuts S are then applied to the ends of the bolts O, where they project through the plate B, and, when the nuts S are tightly turned down, the yoke K, being pulled against the flange I of the coupling G, presses the projecting periphery of the coupling into the soft gasket H, and effects a water-tight joint, as will be understood.

10 From the foregoing it will be noted that the bowl is supported entirely from the soil pipe, and that there is no necessity of any supporting members in the room where the bowl is located. The flange I is clamped by 15 the yoke K, at all points around the periphery of said flange, and as long as the nuts S are in operative position, the entire outer periphery of the coupling G is clamped into the soft gasket H, assuring a water-tight 20 joint. To attain access to the extension E, for clearance of accumulations, if necessary, the nuts S are turned off the bolts O, and the bowl A removed.

In certain cases, where deemed desirable, 25 the arm N of the yoke K may be provided with an apertured rearward projection T, located below the body of the yoke, and adapted to receive a post U, screw-threaded at its upper portion to receive a nut V, as shown in 30 Fig. 1. By raising or lowering the nut V, slight adjustments of the coupling G are permitted, for the purpose of alignment in centralizing it with the wall opening in the wall C.

35 Modifications of the herein described structure may be suggested to those skilled in the art, but my invention covers all embodiments falling fairly within the scope of the appended claims, and it is to be clearly 40 understood that the fixture is adapted for use in connection with slop sinks, and other sanitary plumbing fixtures analogous to closets.

I claim:

45 1. In combination with a soil pipe, a closet fitting having a waste outlet and a gasket surrounding said outlet, a coupling secured to said pipe and establishing communication with said outlet, a yoke surrounding 50 said coupling and provided with a groove in its periphery, a peripheral flange carried by said coupling and adapted to enter said groove, and means for connecting said yoke to said fitting and to simultaneously cause 55 it to press against said flange and draw said coupling into close contact with said gasket.

60 2. In combination with a soil pipe, a closet fitting having a waste outlet and a gasket surrounding said outlet, a coupling secured to said pipe and establishing communication with said outlet, a yoke surrounding said coupling and provided with a 65 groove in its periphery, a peripheral flange

carried by said coupling and adapted to enter said groove, said flange being also positioned for contact by the face of said yoke opposite said groove, and means for connecting said yoke to said fitting and to simultaneously cause it to press against said flange and draw said coupling into close contact with said gasket.

3. In combination with a soil pipe, a closet fitting having a waste outlet and a gasket surrounding said outlet, a coupling secured to said pipe and establishing communication with said outlet, a peripherally extending flange carried by said coupling, a yoke surrounding said coupling and carrying a laterally and upwardly extending lip forming between the lip and the adjacent face of the yoke a groove adapted to receive said flange, and means for drawing said yoke against said flange to press the coupling into close contact with said gasket.

4. In combination with a soil pipe, a closet fitting having a waste outlet and a gasket surrounding said outlet, a coupling secured to said pipe and establishing communication with said outlet, a yoke carrying a groove on a portion of its periphery, said yoke surrounding the coupling and being provided with a central oval-shaped opening whereby the yoke may be moved to a position such that the flange of the coupling is received in said groove, and means for connecting the yoke to said fitting and simultaneously drawing the coupling into close contact with said gasket.

5. In combination with a soil pipe, a closet fitting having a waste outlet, a gasket surrounding said outlet, and a coupling establishing communication between said pipe and said outlet, a peripherally extending rearwardly facing flange on said coupling, a yoke surrounding the coupling behind 105 said flange, and means for connecting the yoke to said fitting and for simultaneously drawing the said yoke against the rear face of said flange, whereby to press the coupling into close contact with said gasket.

6. In combination with a soil pipe, a closet fitting having a waste outlet, a gasket surrounding said outlet and a coupling establishing communication between said outlet and said pipe, a radially extending rearwardly facing flange carried by said coupling, a yoke surrounding said coupling and provided with a surface adapted to contact one portion of the rear face thereof and with a groove adapted to receive a portion of said flange, and means for connecting the yoke to the fitting and for simultaneously drawing the coupling into close contact with said gasket substantially as described.

In testimony whereof I affix my signature.

TOBIAS J. KAUFMAN.
